UNITED STATES PATENT OFFICE

EMILE DÉCHERY, OF PARIS, FRANCE, ASSIGNOR TO "JERRY DRESS CO. INC." OF NEW YORK, N. Y.

DESIGN FOR A TEXTILE FABRIC OR SIMILAR ARTICLE

Application filed April 27, 1932. Serial No. 43,620. Term of patent 3½ years.

To all whom it may concern:

Be it known that I, EMILE DÉCHERY, a citizen of the French Republic, residing at Paris (Seine), France, 5, rue de l'Aqueduc, have invented a new, original, and ornamental Design for a Textile Fabric or Similar Article, of which the following is a specification, reference being had to the accompanying drawing, forming a part thereof.

The figure is a plan view of a textile fabric showing a complete unit of my new design. The drawing is lined to indicate shading.

I claim:

The ornamental design for a textile fabric or similar article as shown and described.

In testimony whereof I have signed my name to this specification.

EMILE DÉCHERY.
